PICKET FENCE

John S. Case, Towson, Md., assignor to Anchor Post Products, Inc., Baltimore, Md., a corporation of New Jersey

Filed Mar. 15, 1962, Ser. No. 69,273

Term of patent 14 years

(Cl. D28—1)

FIG. 1 is a front elevational view of a section of a picket fence showing my new design;

FIG. 2 is a fragmentary perspective view of one end of the picket fence of FIG. 1;

FIG. 3 is a cross section taken along line 3—3 of FIG. 2;

FIG. 4 is a cross section taken along line 4—4 of FIG. 2;

FIG. 5 is a cross section taken along line 5—5 of FIG. 2.

I claim:

The ornamental design of a picket fence, as shown.
